INTEGRATOR MECHANISM FOR LINE SECTIONALIZERS

James M. Wallace and Andrew W. Edwards, East
McKeesport, Pa., assignors to Westinghouse
Electric Corporation, East Pittsburgh, Pa., a
corporation of Pennsylvania

Application July 21, 1950, Serial No. 175,274

17 Claims. (Cl. 200—109)

1

Our present invention relates to integrator-mechanisms for line-sectionalizers. More particularly, it relates to a novel type of integrator-mechanism which has no time-delayed parts, thereby avoiding the cost and the unreliable operation which have been involved in the various dashpots, mechanical escapements, and other time-delay mechanisms which have been employed in the past.

Line-sectionalizers are used on rural distribution-lines in cooperation with a recloser which is used for supplying electrical power to the line. The recloser responds to fault-currents by automatically opening the line, and immediately reclosing it again. If the fault has not automatically cleared itself during the interval during which the electric power was off of the line, the recloser again operates, for a predetermined number of counts, usually four, as long as the fault-current appears whenever the recloser-contacts are closed. At the end of this predetermined number of counts, the recloser automatically locks itself out, so that the line is not energized again.

The distribution-line or system is subdivided into a number of sections by one or more line-sectionalizers, each of which responds to fault-currents which occur in its own section. Each sectionalizer counts a predetermined number of rapidly recurring overcurrent-conditions, this sectionalizer-count being less than the recloser-count, and finally the sectionalizer opens its line-contact during a no-current period of the recloser, thus removing or deenergizing the section where a permanent or non-self clearing fault exists, and permitting the rest of the distribution-system to continue in service.

The counting mechanisms which are used in the sectionalizers and in the recloser are called integrators. It is necessary that these integrators shall be automatically self-resetting, and this resetting-operation has heretofore been usually accomplished with the aid of timing devices.

Our present invention relates to integrators for the line-sectionalizers. Since these sectionalizers do not open their line-contacts when there is any line-current flowing, they may be made relatively inexpensively, being nothing more than an integrator and a disconnect-switch. It is essential, therefore, that the integrator shall be as simple and as inexpensive as possible.

In our present integrator, we use an electromagnet having an armature which moves back and forth, from its unattracted position to the

2

position to which it is attracted when the integrator-coil is energized with an adequate overcurrent. The movements of the armature toward its attracted position are used to advance a counter-rod in a step-by-step fashion, and each time the armature moves back, after advancing the counter-rod, a holding-detent engages the rod and holds it in an advanced position. As long as overcurrent-conditions continue to appear, in the integrator-coil, followed by no-current periods, the above-described armature-movement continues to notch the counter-rod still further forward. According to our invention, a normal current-condition, as distinguished from an overcurrent-condition, is used to effect the release of the holding-detent, and permit the instant resetting of the counter-rod, regardless of the number of notches through which it had been advanced.

20 Our invention provides a novel means whereby a single armature, which is biased towards an intermediate position, will move in one direction in response to normal currents, and in the other direction in response to overcurrents, with mechanism arranged to notch the counter-rod forward in response to the overcurrent-movements, and to trip out the holding-detent in response to the normal-current condition.

25 A further feature of our invention involves a special latching-means whereby the final response of the integrator is obtained during a no-current period, and not during the last overcurrent-period which is permitted by the number of counts which are responded to by the integrator.

30 With the foregoing and other objects in view, our invention consists in the apparatus, systems, mechanisms, parts, and methods of design and operation, hereinafter described and claimed, and 35 illustrated in the accompanying drawing, the single figure of which is a diagrammatic vertical sectional view of an integrator-mechanism illustrative of our invention.

The description and explanation of our invention may conveniently be divided into three parts. First, there is an electromagnet-part 1, which is shown at the top of the figure, and which has a movable armature 2 which serves as a three-position movable operating-member which is biased 40 toward its intermediate position, and which moves to one extreme position in response to current-values within a normal current-range, and which moves to its other extreme position in response to currents in excess of said normal range. Next, 45 on the drawing, comes the counting mechanism

1, which counts the number of discrete over-current-movements of the armature 2, which occur before there is any period during which normal current flows. And finally, at the bottom of the figure, there is the special latch-mechanism 4 which stores up information that the desired number of overcurrent operations have been obtained, until there is no longer an overcurrent, after which a response to the integrator-mechanism is permitted.

The electromagnet 1 is a special current-responsive mechanism comprising a coil 5 which is a part of a stationary frame including an upper pole-piece 6 and a lower pole-piece 7. These two pole-pieces are joined by a tube 8 of insulation or other non-magnetizable material. This electromagnet frame may be supported in any way, as by means of a support-bracket 9. In the illustrated embodiment of our invention, the insulating tube 8 stands in a substantially vertical position, and for convenience it will be described as if it were in that position, although it is obvious that we are not limited to a vertical position.

Inside of the insulating tube 8, at the upper end thereof, we provide a movable upper pole-piece 11, which is slidably movable within the tube 8, and which is pressed up against the top of the tube by means of a compression-spring 11' which is shown as abutting against an insulating or non-magnetizable sleeve 12 which is secured within the tube 8.

The armature 2 is axially movable inside of the sleeve 12. Secured to the bottom of this armature 2 is an axially depending magnetizable armature-rod 13, which extends freely through an axial hole 14 through the lower pole-piece 7, and on down to the counting-mechanism 3 which will be subsequently described. An intermediate portion of the armature-rod 13 is provided with a washer or shoulder 15, which is held between two compression-springs 16 and 17, which bias the armature to an intermediate position which is below the normal spring-held position of the movable upper pole-piece 11, and above the lower pole-piece 7, as shown in the drawing. That portion of the armature-rod 13 which extends up between the lower pole-piece 7 and the armature 2 is of such restricted cross-sectional area that it is saturated during overcurrent conditions, but not during normal-current conditions.

As a result of this electromagnet-construction, the armature-rod 13, in its unsaturated condition, will carry the magnetic flux from the lower pole-piece 7 to the armature 2, during a normal range of current-values, thus permitting the top of the armature 2 to be attracted upwardly to the bottom of the movable upper pole-piece 11, during these normal-current conditions. The spring 11', which holds up the movable upper pole-piece 11 in its normal uppermost position, is strong enough to resist the pull of the armature 2 during these normal-current conditions, so that the armature moves upwardly to meet the upper pole-piece during said conditions.

When a predetermined overcurrent-condition is obtained, the design is such that the magnetizable armature-rod 13 saturates, thus allowing flux to flow in the air gap between the top of the lower pole-piece 7 and the bottom of the armature 2. The armature 2 is thus attracted in both directions, both downwardly toward the lower pole-piece 7, and upwardly toward the movable upper pole-piece 11. The strong magnetic flux due to the overcurrent-value is enough to overcome the bias of the spring 11', so that the

movable upper pole-piece 11 is now attracted downwardly to the top of the armature 2, and then the entire force of the magnetic flux in the gap between the armature 2 and the lower pole-piece 7 is effective to pull the armature 2 down into engagement with the lower pole-piece 7. In this manner, the armature 2 moves downwardly in response to overcurrents, and upwardly in response to normal currents, and the armature 10 returns to its predetermined intermediate position during zero currents or currents below the normal range of load-currents for which the apparatus is designed.

The counting-mechanism 3 and the latching-mechanism 4 of the integrator are housed in a downwardly depending tube 18, which is secured to the bottom of the lower pole-piece 7, so that the two tubes 8 and 18 serve as coaxial extensions of each other.

The counting-mechanism 3 includes an axially movable operating-member 20 which is carried by the lower end of the armature-rod 13, and an upwardly biased axially disposed counter-bar 21. As shown, the lower end of the counter-bar is biased upwardly, toward its resetting position, by means of a compression-spring 21' which presses up on a shoulder 21" carried by the counter-bar 21.

The operating-member 20 slides freely up and down within the lower tube 18, in accordance with the movements of the armature 2. The lower end of this operating-member 20 is provided with a lug 22 to which is pivoted a tiltable pawl or ratchet 23, which serves as a one-way drive-mechanism for causing the counter-bar 21 to take one step of a step-by-step downward advance-movement away from the armature-position, each time the armature moves downwardly to the fixed lower pole-piece 7 during an overcurrent-condition in the coil 5. The pawl or ratchet 23 is yieldably canted, as by means of a spring 23', so that its lower edge engages one of a series of notches 24 on the counter-bar 21, each time the armature 2 moves downwardly to its overcurrent position.

As shown in the drawing, the top of the operating-member 20 is provided, on one side, with a slot 25 which is wide enough to receive a lug 26 which extends inwardly from the side wall of the lower tube 18. This lug 26 is used to pivotally support a holding detent 27, which is biased toward a canted position by means of a suitable spring 27'. This holding-detent thus engages any one of a second series of notches 28 on the counter-bar 21.

The result of the foregoing construction is that, each time the armature 2 moves downwardly to its overcurrent position, the advancing-pawl 23 notches the counter-bar 21 downwardly one step in its step-by-step advancement. Whenever the armature returns upwardly to its intermediate unattracted position, the counter-advancing pawl 23 moves up, readily for engagement with the next notch 24 in the counter-bar 21, while the holding-detent 27 catches behind one of the holding-notches 28, and causes the counter-bar 21 to retain at least a portion of its downwardly notched advance. This step-by-step downward advancement of the counter-bar 21 continues every time there is an overcurrent-condition, followed by a zero-current condition, or a current-strength less than the minimum value necessary to move the armature to the upper limit of its travel.

If the fault which caused the overcurrent-

5

condition clears itself before the counter-bar 21 completes its predetermined number of advance-steps, then, of course, there will be no further notching-advance of the counter-bar 21. Ordinarily, when the fault disappears, there will be a normal current-flow which is sufficient to lift the armature 2 to its uppermost position. For example, the current which is required to lift the armature 2 may be in the range between 20% and 100% of the normal full-load current in the line in which the integrator-mechanism is connected, or any other suitable normal current-range may be chosen.

When such a normal current-value is established in the coil 5, the armature 2 rises to its topmost position, drawing up the operating-member 20 with it. When this operating-member 20 moves upwardly to its topmost position, the bottom of its slot 25 engages an edge of the holding-detent 27, and straightens it into a horizontal position in which it releases its engagement with one of the holding-notches 28, and permits the counterbar 21 to instantly reset itself, by moving upwardly to its initial unadvanced position, under the impetus of its biasing-spring 21'. It will be noted that this resetting-operation is instantaneous, and independent of the number of advance-steps which have been made by the counter-bar 21, being dependent only upon the occurrence of a current-value in the normal range.

If, after the fault has cleared itself, and before the counter-bar 21 has completed its prescribed number or count of advance-steps, the fault-free load on the line should be so small that the load-current is not large enough to pick up the armature 2 to its topmost position, then the integrator or counter-mechanism will remain in its partially advanced position until normal current does appear; or if a fault should occur before this normal current appears, then the counting-mechanism will resume its count from the point at which it previously left off.

It will be noted that the counting-operation of the counting-mechanism is not dependent upon the rapidity of the occurrence of successive overcurrent conditions, but only upon the occurrence of successive overcurrent-conditions, separated by no-current conditions, regardless of the time-intervals between successive overcurrent-conditions, so long as no normal current-values appear in the meantime.

When the counter-bar 21 has been downwardly advanced through its predetermined number of advance-steps, some means must be provided for effecting a desired integrator-response, such as opening the line-contact (not shown) of a line-sectionalizer.

It will be noted, from the foregoing description, that the particular counting-device 3 which is illustrated uses an operating-member 20 which is disposed on the overcurrent side of the travel-limits of the armature 2, so that the operating-member 20 is advanced during the movement of the armature toward its overcurrent position, as distinguished, for example, from advancing when the armature returns from its overcurrent position. Since this is the case, it is usually necessary or desirable to provide some arrangement for absorbing the information that the counter-bar 21 has reached the limit of its predestined advancing movement, and to retain this information until the last overcurrent-condition is interrupted, usually by recloser (not shown). For this reason, a special latch-mecha-

6

nism is usually desirable, as shown at 4 at the bottom of the drawing.

In the illustrated latch-mechanism 4, the bottom of the integrator is equipped with an axially disposed response-rod 30, which extends up a little way into the bottom of the tube 18, and which is biased upwardly toward a responding position, as by means of a spring 30'. This response-rod 30 is provided with a shoulder 31, above which is disposed a suitable latch 32 which is carried by the tubular housing 18 at a point between the response-rod 30 and the counter-bar or rod 21. This latch 32 is normally in such position that it engages the top of the shoulder 31 of the response-member 30, and holds said response-member against upward movement in its biased responsive position.

The particular type of latch 32 which is shown in the drawing is in the form of a thin axially disposed tube 32', the top end of which is secured in an annular plug 33 which is secured within the housing-tube 18. The lower end of the latch-tube 32' is slit into a plurality of fingers, which are bent inwardly to form a tulip-type end 34. The inner diameter of the latch-tube 32' is sufficiently large to permit the response-rod shoulder 31 to move upwardly into said latch-tube, when the tulip-fingers 34 are expanded. A slide sleeve or inverted cup-member 35 is disposed inside of the latch-tube 32', in the path of the downwardly advancing counter-bar 21, so that, when the counter-bar makes its final downward advance-movement, it pushes the inverted cup-member 35 downwardly, causing it to expand the tulip-fingers 34, thus releasing the latch 32 from its engagement with the response-rod shoulder 31.

It will be observed that, at the same time when the last advance-movement of the counter-bar 21 releases the latch 32, the counter-bar 21 also abuts down against the inverted cup-member 35, which in turn abuts down against the response-rod shoulder 31, thus mechanically holding said response-rod 30 against substantial movement in its upward responding-direction, as long as the counter-bar 21 is in its fully advanced downward-position.

The last downward advance of the counter-bar 21, when the armature 2 moves down to its overcurrent-position for the last time, is somewhat lower than the counter-bar position in which it will be retained by the last holding-notch 28, under the action of the holding-detent 27, when the armature 2 moves back upwardly again. In other words, when the armature 2 moves back upwardly away from its lowermost overcurrent-position for the last time, the counter-bar 21 is withdrawn back for a fraction of its last advance-step, before said counter-bar reaches its last detent-held advanced-position. This slight upward withdrawal of the counter-bar 21 is requisite only upon the cessation of the last overcurrent-condition, and it permits the response-rod 30 to make a substantial or adequate upward-movement, in its responding direction, under the impetus of its spring 30'. This upward movement of the response-rod 30 constitutes the final response-operation of the integrator-mechanism. This response-operation may be used to control any desired mechanism, for instance a latch-member 36, which is to be controlled by the integrator-mechanism.

While we have illustrated our invention in only a single illustrative form of embodiment, we wish it to be understood that our invention is not

all limited to the precise details which have been shown, and we desire that our appended claims may be accorded the broadest construction consistent with their language.

We claim as our invention:

1. An integrator-mechanism comprising: a three-position movable operating-member, biasing means biasing said operating-member toward its intermediate position; current-responsive means for moving said movable operating-member to one extreme position in response to current-values within a normal current-range, and for moving said movable member to its other extreme position in response to currents in excess of said normal range; a movable counter-member which is biased toward an inoperative position; a one-way drive-mechanism operatively connecting the operating-member and the counter-member for imparting one step of a step-by-step advance to said counter-member in response to movement of said operating-member to one of its extreme positions; a holding-detent for engaging and holding said counter-member in advanced positions; and means for releasing said holding-detent in response to movement of said operating-member to the other of its extreme positions.

2. The invention as defined in claim 1, characterized by said current-responsive means comprising: a magnetizing coil having two pole pieces; a movable armature which is biased toward an intermediate position spaced between said two pole pieces; a first one of said pole pieces being movable toward said armature and having biasing-means for holding it away from the armature with a force which is strong enough to withstand the magnetic attraction which is caused by normal current-values in the coil, but not strong enough to resist overcurrent-values, and means providing a saturable flux-path joining said armature to the second pole piece while permitting the armature to move in either direction, whereby the attraction of said second pole piece for the armature is held at a reduced value by said saturable flux-path as long as said path remains unsaturated, and is increased upon said path becoming saturated on overcurrent-values.

3. The invention as defined in claim 1, characterized by said current-responsive means comprising: a non-magnetic tubular member; a magnetizing coil for causing a magnetic flux to flow axially in a portion of said tubular member; a fixed pole-piece in said tubular member at one end of the region through which axial flux flows; an axially movable pole-piece in said tubular member at the other end of the region through which axial flux flows; an armature within said tubular member, said armature being axially movable between said pole-pieces; means for biasing said armature toward an intermediate position spaced between said two pole-pieces; biasing-means for holding said movable pole-piece in an undisplaced position away from the armature with a force which is strong enough to withstand the magnetic attraction which is caused by normal current-values in the coil, but not strong enough to resist overcurrent-values; and a saturable means whereby the attraction of said fixed pole-piece for the armature is strongly reduced as long as said saturable means remains unsaturated, said saturable means becoming saturated on overcurrent-values.

4. The invention as defined in claim 1, characterized by said current-responsive means comprising: a tubular member of non-magnetic ma-

terial; a magnetizing coil for causing a magnetic flux to flow axially in a portion of said tubular member; a centrally perforated fixed pole-piece in said tubular member at one end of the region through which axial flux flows; an axially movable pole-piece in said tubular member at the other end of the region through which axial flux flows; an armature within said tubular member, said armature being axially movable between said pole-pieces; means for biasing said armature toward an intermediate position spaced between said two pole-pieces; biasing-means for holding said movable pole-piece in an undisplaced position away from the armature with a force which is strong enough to withstand the magnetic attraction which is caused by normal current-values in the coil, but not strong enough to resist overcurrent-values; and a saturable armature-rod secured to said armature and passing slidably through the central perforation in the fixed pole-piece, whereby the attraction of said fixed pole-piece for the armature is strongly reduced by the flux-path which is provided by said armature-rod as long as said path remains unsaturated, said path becoming saturated on overcurrent-values.

5. A current-responsive mechanism comprising: a magnetizing coil having two pole pieces; a movable armature means biasing said armature toward an intermediate position spaced between said two pole pieces; a first one of said pole pieces being movable toward said armature and having biasing-means for holding it away from the armature with a force which is strong enough to withstand the magnetic attraction which is caused by normal current-values in the coil, but not strong enough to resist overcurrent-values, and means including a saturable armature extension movable relative to the second pole piece for providing a saturable flux-path joining said armature to the second pole piece while permitting the armature to move in either direction, whereby the attraction of said second pole piece for the armature is strongly reduced by said saturable flux-path as long as said path remains unsaturated, said path becoming saturated on overcurrent-value.

6. A current-responsive mechanism comprising: a non-magnetic tubular member; a magnetizing coil positioned relative to the tubular member for causing a magnetic flux to flow axially in a portion of said tubular member; a fixed pole-piece in said tubular member at one end of the region through which axial flux flows; an axially movable pole-piece in said tubular member at the other end of the region through which axial flux flows; an armature within said tubular member, said armature being axially movable between said pole-pieces; means for biasing said armature toward an intermediate position spaced between said two-pieces; biasing-means for holding said movable pole-piece in an undisplaced position away from the armature with a force which is strong enough to withstand the magnetic attraction which is caused by normal current-values in the coil, but not strong enough to resist overcurrent-values; and a saturable means magnetically coupling the armature to the fixed pole-piece whereby the attraction of said fixed pole-piece for the armature is strongly reduced as long as said saturable means remains unsaturated, said saturable means becoming saturated an overcurrent-values so as to permit the attraction of the fixed pole-piece for the armature to increase.

7. An integrator-mechanism comprising: a tubular member substantially of non-magnetic ma-

terial; a magnetizing coil disposed relative to said tubular member for causing a magnetic flux to flow axially in a portion of said tubular member; a fixed pole-piece in said tubular member at one end of the region through which axial flux flows; an axially movable pole-piece in said tubular member at the other end of the region through which axial flux flows; an armature within said tubular member, said armature being axially movable between said pole-pieces; means for biasing said armature toward an intermediate position spaced between said two pole-pieces; biasing-means for holding said movable pole-piece in an undisplaced position away from the armature with a force which is greater than that of the magnetic attraction caused by normal current-values in the coil, but not strong enough to resist overcurrent-values; a saturable means magnetically connecting the fixed pole piece and armature whereby the attraction of said fixed pole-piece for the armature is strongly reduced as long as said saturable means remains unsaturated, said saturable means becoming saturated on overcurrent-values; an operating-member responsive to the movements of said armature within said tubular member; an axially movable counter-bar which is disposed axially within said tubular member; means for biasing said counter-bar toward a limit of its movement; a one-way drive-mechanism operatively connecting the operating member and counter-bar for causing said counter-bar to take one step of a step-by-step advance-movement each time said armature moves in one direction; a holding-detent carried by said tubular member for engaging and holding said counter-bar in advanced positions; and means for causing said operating-member to release said holding-detent each time the armature moves in the other direction.

8. The invention as defined in claim 7, in combination with a response-member which is biased in an axial direction; a latch which is carried by the tubular member, said latch being normally in such position that it engages and holds said response-member against movement in its biased direction; and means whereby the counter-rod, at the termination of its predetermined step-by-step advance, pushes back said latch and at the same time holds said response-member against substantial movement as long as said counter-rod is in its advanced position.

9. A current-responsive mechanism comprising: a tubular member at least a portion of which is of non-magnetic material; a magnetizing coil positioned for causing a magnetic flux to flow axially in a portion of said tubular member; a centrally perforated fixed pole-piece in said tubular member at one end of the region through which axial flux flows; an axially movable pole-piece in said tubular member at the other end of the region through which axial flux flows; an armature within said tubular member, said armature being axially movable between said pole-pieces; means for biasing said armature toward an intermediate position in which it is spaced from each of said two pole-pieces by an air gap; biasing-means for holding said movable pole-piece in an undisplaced position away from the armature with a force which is strong enough to withstand the magnetic attraction which is caused by normal current-values in the coil, but not strong enough to resist overcurrent-values; and a saturable armature-rod secured to said armature and passing slidably through the central perforation in the fixed pole-piece, whereby the attraction of magnetic flux across the air

gap between said fixed pole-piece and the armature is strongly reduced by the flux-path which is provided by said armature-rod as long as said path remains unsaturated, the attraction of the magnetic flux across said air gap increasing upon said path becoming saturated on overcurrent-values.

10. An integrator-mechanism comprising: a tubular member having at least a portion thereof of a non-magnetic material; a magnetizing coil positioned relative to the tubular member for causing a magnetic flux to flow axially in a portion of said tubular member; a centrally perforated fixed pole-piece in said tubular member at one end of the region through which axial flux flows; an axially movable pole-piece in said tubular member at the other end of the region through which axial flux flows; an armature within said tubular member, said armature being axially movable between said pole-pieces; means for biasing said armature toward an intermediate position spaced between said two pole-pieces; biasing-means for holding said movable pole-piece in an undisplaced position away from the armature with a force which is strong enough to withstand the magnetic attraction caused by normal current-values in the coil, but not strong enough to resist overcurrent-values; a saturable armature-rod secured to said armature and passing slidably through the central perforation in the fixed pole-piece, whereby the attraction of said fixed pole-piece for the armature is strongly reduced by the flux-path which is provided by said armature-rod as long as said path remains unsaturated, said path becoming saturated on overcurrent-values; an operating-member carried by the portion of said armature-rod which projects through the fixed pole-piece; an axially movable counter-bar which is disposed axially within said tubular member; means for biasing said counter-bar toward the limit of its movement which is closest to said armature; a one-way drive-mechanism for operatively connecting said counter-bar and armature and causing said counter-bar to take one step of a step-by-step advance-movement away from said armature each time said armature moves to the fixed pole-piece; a holding-detent carried by said tubular member for holding said counter-bar in advanced positions; and means for causing said operating-member to release said holding-detent each time the armature moves to the undisplaced movable pole-piece.

11. The invention as defined in claim 10, in combination with a response-member which is biased in an axial direction toward the end of said counter-rod; a latch which is carried by the tubular member at a point between said response-member and said counter-rod, said latch being normally in such position that it engages and holds said response-member against movement in its biased direction; and means whereby the counter-rod, at the termination of its predetermined step-by-step advance, pushes back said latch and at the same time holds said response-member against substantial movement as long as said counter-rod is in its advanced position; the last advance of said counter-rod being beyond the last position in which said counter-rod is held by said holding-detent, whereby, upon cessation of said overcurrent, the counter-rod is withdrawn back to said last detent-held position and permits said response-member to follow said counter-rod past said latch.

12. An integrator-mechanism comprising: a

tubular member; a magnetizing coil for causing a magnetic flux to flow axially in a portion of said tubular member; an armature within said tubular member, said armature being movable between a retracted position and an advanced position to which said armature is drawn by an overcurrent-energization of said coil; means for biasing said armature toward the retracting direction; an axially movable counter-bar which is disposed axially within said tubular member; means for biasing said counter-bar toward an inoperative position; a one-way drive-mechanism connecting the armature and counter-bar for imparting one step of a step-by-step advance to said counter-bar each time said armature advances to its overcurrent-positions; a holding-detent carried by said tubular member for holding said counter-bar in advanced positions; a response-member which is biased in an axial direction toward the end of said counter-rod; a latch which is carried by the tubular member at a point between said response-member and said counter-rod, said latch being normally in such position that it engages and holds said response-member against movement in its biased direction; and means whereby the counter-rod, at the termination of its predetermined step-by-step advance, pushes back said latch and at the same time holds said response-member against substantial movement as long as said counter-rod is in its advanced position; the last advance of said counter-rod being beyond the last position in which said counter-rod is held by said holding-detent, whereby, upon cessation of said overcurrent, the counter-rod is withdrawn back to said last detent-held position and permits said response-member to follow said counter-rod past said latch.

13. An integrator-mechanism comprising: an operating-member which moves between a retracted position and an advanced position; a movable counter-member which is biased toward an inoperative position; a one-way drive-mechanism effectively connecting the operating-member and counter member for imparting one step of a step-by-step advance to said counter-member each time said operating-member moves to its advanced position; a holding-detent for holding said counter-member in advanced positions; a response-member which is biased toward the advancing end of said counter-member; a latch which is disposed at a point between said response-member and said counter-member, said latch being normally in such position that it holds said response-member against movement in its biased direction; and means whereby the counter-member, at the termination of its predetermined step-by-step advance, pushes back said latch and at the same time holds said response-member against substantial movement as long as said counter-member is in its advanced position; the last advance of said counter-member being beyond the last position in which said counter-member is held by said holding-detent, whereby, when said operating-member moves back from its last advanced position, the counter-member is withdrawn back to said last detent-held position and permits said response-member to follow said counter-member past said latch.

14. An integrator-mechanism comprising: an operating-member which moves between a retracted position and an advanced position; a movable counter-member which is biased toward an inoperative position; a one-way drive-mechanism providing an operating connection between the operating-member and counter-member for

imparting one step of a step-by-step advance to said counter-member each time said operating-member moves to its advanced position; a holding-detent for holding said counter-member in advanced positions; a response-member which is biased toward a responding position; a latch for normally holding said response-member from responding; and means whereby the counter-member, at the termination of its predetermined step-by-step advance, releases said latch and at the same time mechanically holds said response-member against substantial movement in its responding direction as long as said counter-member is in its fully advanced position; the last advance of said counter-member being beyond the last position in which said counter-member is held by said holding-detent, whereby, when the operating-member moves back from its last advanced position, the counter-member is withdrawn back to said last detent-held position and permits said response-member to make a substantial movement in its responding direction.

15. An integrator-mechanism comprising: an electromagnet device having a magnetizing coil and an armature which is movable from a predetermined unattracted position to a predetermined attracted position to which it is attracted by the magnetic flux produced by a predetermined overcurrent in the coil; a movable counter-member which is biased toward an inoperative position; a one-way drive-mechanism effectively connecting the armature and the counter-member for imparting one step of a step-by-step advance to said counter-member each time said armature moves to its overcurrent-position; a holding-detent for holding said counter-member in advanced positions; a response-member which is biased toward a responding position; a latch for normally holding said response-member from responding; and means whereby the counter-member, at the termination of its predetermined step-by-step advance, releases said latch and at the same time mechanically holds said response-member against substantial movement in its responding direction as long as said counter-member is in its fully advanced position; the last advance of said counter-member being beyond the last position in which said counter-member is held by said holding-detent, whereby, when the armature moves back from its overcurrent position for the last time, the counter-member is withdrawn back to said last detent-held position and permits said response-member to make a substantial movement in its responding direction.

16. An integrator mechanism comprising: an operating member having three operating positions, biasing means actuating said member to one of the positions, electromagnetic means for moving said operating member to another one of the positions in response to a current value within a normal current range and for moving said operating member to the other of the positions in response to a current in excess of said normal range, a movable counter-member normally disposed in a rest position, means operatively connecting the operating-member and the counter-member for imparting a one way step-by-step advance of said counter-member in response to repeated movements of said operating-member to said other of the positions, and means operable in response to movement of the operating-member to its other extreme position to effect return of the counter-member to its rest position.

17. In an integrating-mechanism, a movable

13

armature, biasing means biasing the armature to an intermediate position, electromagnetic means including a magnetizing coil having a pair of pole pieces disposed on opposite sides of the armature for moving it to one extreme position in response to currents within a normal operating range and to its other extreme position in response to a current in excess of said normal range, a movable counter-member biased to an inoperative position, drive means operatively connecting the counter-member and the armature to effect a one way step-by-step advance of said counter-member in response to movement of said armature to one extreme position, and means operable in response to movement of the armature to its other extreme position to

5

14

actuate a portion of the drive means to effect return of the counter-member to its inoperative position.
